Pierre Barnes
ATTORNEY

UNITED STATES PATENT OFFICE.

CALVIN H. HAGAN, OF SEATTLE, WASHINGTON, ASSIGNOR TO CHARLES F. WHITTLESEY,
OF SEATTLE, WASHINGTON.

FIREPLACE-FURNACE.

1,298,495.

Specification of Letters Patent. Patented Mar. 25, 1919.

Application filed April 25, 1918. Serial No. 230,787.

To all whom it may concern:

Be it known that I, CALVIN H. HAGAN, a citizen of the United States, residing at Seattle, in the county of King and State 5 of Washington, have invented certain new and useful Improvements in Fireplace-Furnaces, of which the following is a specification.

This invention relates to fire-place heaters; and its object is the perfecting of devices of this character to render the same more economical and efficient in operation.

The invention consists in the novel adaptation and arrangement of the smoke flue, and of the chambers and passages in which air is introduced and heated; and also in the provision of novel devices for moistening the heated air in a substantially uniform manner.

20 The invention further consists in the novel features of construction and the combination thereof as will hereinafter be described and claimed.

In the accompanying drawings,—

25 Figure 1 is a front elevational view, shown partly in section of a fire-place furnace embodying my invention, said section being taken substantially through 1—1 of Fig. 2. Fig. 2 is a section on line 2—2 of Fig. 1. Fig. 3 is a sectional view through 3—3 of Fig. 2. Fig. 4 is a section through 4—4 of Fig. 3.

In carrying out my invention, I provide a casing which is divided into upper and 35 lower portions A and B by a floor partition 5, the same preferably extending in front of said upper portion to furnish a mantel shelf 6.

40 The space within said lower portion is divided by a transverse wall 7, into two chambers 8 and 9. Extending from the front casing wall 10 to the wall 7 are side and top walls 11 and 12 of the fire-place F proper. The top wall 12 of said fire-place 45 inclines upwardly as shown in Fig. 2 to the lower end of a smoke flue consisting of a series of connected inclined elements 13, 13¹ and 13² disposed within the upper part of the chamber 8 and connected by a flue member 13³ which extends through the chamber 14 in the part A to a pipe 15 leading to a chimney flue not shown.

Extending upwardly through the chamber 9 and at one side of the same, is a cold

air inlet duct 16 having adjacent to its 55 lower end an opening 17 into the chamber 9 and communicating from its upper end through an aperture 18 in the floor partition 5 with the chamber 14. The lower end of the duct 16 is connected through floor 60 opening 19 with the upper end of an air supply pipe 20, which extends for a distance, of ten feet for example, below the bottom of the heater. The air supply pipe 20 also communicates through a floor opening 65 21 (Fig. 4) with the chamber 8 at one side of said fire-place. At the other side of the fire-place, chamber 8 is provided with a floor opening 22 for connection with a hot air outlet pipe 23 which extends to a 70 less distance downwardly than the air supply pipe 20 and, as shown in Figs. 1 and 3, is formed with a bend 23¹ whence it is led horizontally to a floor register, not shown, or it may be connected by branches to a 75 plurality of registers.

The hot air pipe 23 also communicates from the bottom of a diving duct 24 through a floor opening 22¹, said diving duct is afforded by a partition 25 at the opposite 80 side of chamber 9 from the air inlet duct 16. The walls 11 and 12 within the chamber 8, it is noted, afford a rising duct 8¹ and a diving duct 8² at opposite sides of the fire-place.

85 Provided in the chamber 9 and in juxtaposition with the wall 7 at the rear of the fire-place F is a water receptacle 26 which is divided by partitions 27 extending down from the top 26¹ of the receptacle to furnish a number of compartments, indicated in Fig. 3 by 14^a, 8^a and 24^a, which communicate with each other, as at 28, below the several partitions. 29 represents a pipe connected to said receptacle for supplying 90 water thereto to a predetermined height above the lower ends of the partitions to provide a steam containing space in each of the compartments.

95 Leading from the compartments 14^a, 8^a and 24^a, into the respective chambers 14 and 8 and the diving duct 24 for the chamber 9 are pipes 14^b, 8^b and 24^b for the purpose of conducting steam to suitably moisten the air. The air chamber 14 is provided 100 with a hot air outlet 30 which, as illustrated in Fig. 3 is disposed at the top to supply, for instance an upstairs room.

The operation of the invention may be explained as follows:

The heat generated in fire-place F is conducted through the inclosing partitions and walls to heat the air in the chambers 8 and 9 to a high temperature, the heating of the air in chamber 8 is also derived from the heat accompanying the smoke and other gaseous combustion products through the medium of the flue members 13, 13¹ and 13².

The air within the chamber 14, in the present embodiment is warmed only from contacting with the heated wall of the flue 13². The air within chambers 8 and 9 upon being warmed expands and is caused to escape through the diving ducts 8¹ and 24, to be replaced by cooler air from the pipe 20. By reason of the last named pipe extending from a considerable distance below the pipe 23, the air will be siphoned through the pipes and chambers, and in passing through the relatively large chambers 8 and 9 the flow of the fluid will be retarded to enable it to become highly heated by contacting with the hot fire-place walls or from heat which is radiated from the latter. The apparatus for vaporizing water to add moisture to the heated air within the chambers is an important part of my invention. The water in the receptacle 26 being maintained in a plane higher than the lower ends of the partitions thereby provides individual compartments in which steam or vapor is collected for use in the respective chambers instead of discharging the vapor to all of the air heating chambers from a single steam space which will give an uneven supply of the same instead of being delivered uniformly as by the present devices.

What I claim, is:—

1. In a fire-place furnace, a casing divided by partitions to afford a front fire-place and a pair of superposed air heating chambers, a smoke flue extending from the fire-place through the upper one of said chambers, air inlet and outlet openings in both of said chambers, said fire-place being interposed between the openings of the lower one of said chambers to afford rising and diving ducts at opposite sides of the fire place, and partitions provided between the openings of the lower chamber to afford rising and diving ducts therein.

2. In a fire-place furnace, having a fire-place and a plurality of air heating chambers, means to respectively admit cold air into, and withdraw the heated air from the lower ends of said chambers, a water-vaporizing receptacle provided in one of said chambers and in heating relation to said fire-place, said receptacle being divided into a number of compartments, a water supply

pipe common to all of said compartments, and steam conducting pipes leading from the several compartments into the respective air chambers.

3. In a fire-place furnace, the combination with two air heating chambers, a fire-place extending into one of said chambers to the front wall of the other chamber, air inlet and outlet openings adjacent to the bottoms of said chambers at opposite sides of the latter, a third air heating chamber in superposed relation to the aforesaid chambers and having air inlet and outlet openings respectively at the lower and upper ends of the same, and a smoke flue extending from the fire-place through one of the lower chambers and said upper chamber, of a water receptacle provided in one of the lower chambers, partitions dividing said receptacle into a number of communicating compartments and affording a plurality of non-communicating steam spaces, and pipes leading from such steam spaces to the respective chambers.

4. A fire-place furnace, comprising a casing containing a fire-place, and two air heating chambers having walls which constitute the walls of said fire-place, said chambers being provided at their bottoms with air inlets and outlets at opposite sides of the furnace, a water-receptacle within one of said chambers and in juxtaposition with the rear wall of said fire-place, means to supply water to said receptacle, and vapor conducting pipes extending from the steam space provided in the receptacle to the respective chambers.

5. A fire-place furnace consisting of a casing having a fire-place at the front, an air chamber above said fire-place, a second chamber at the rear of said fire-place, a partition in the second named chamber to provide a diving duct extending downwardly from the upper end of the latter, a cold air inlet pipe extending from below the furnace and communicating with the lower ends of both of said chambers at the sides thereof remote from said diving duct, hot air outlet pipes communicating with the first named chamber and said diving duct, the outlet pipe of the diving duct extending downwardly below the furnace to a distance less than that of said inlet pipe, and a smoke flue for said fire-place extending upwardly through the first named chamber.

Signed at Seattle, Washington, this 18th day of April, 1918.

CALVIN H. HAGAN.
